UNITED STATES PATENT OFFICE.

ROY A. NELSON, OF CHICAGO, ILLINOIS.

REINFORCED STEEL PLATE.

Specification of Letters Patent. Patented Aug. 29, 1922.

1,427,120.

Application filed August 11, 1919. Serial No. 316,539.

To all whom it may concern:

Be it known that I, ROY A. NELSON, a citizen of the United States, residing at Chicago, in the county of Cook and State of Illinois, have invented a certain new and useful Improvement in Reinforced Steel Plates, of which the following is a specification.

The object of my invention is to provide simple, strong, durable and practically inexpensive means for strengthening all-steel doors (such as are used on freight cars and the like), panel steel floors, partitions and similar devices, so that they will easily and effectually withstand all necessary stress.

My invention consists of certain details of construction hereinafter set forth, pointed out in my claim and illustrated in the accompanying drawings, in which:

20 Fig. 1 shows a portion of the side of a freight car and an all-steel door, made in accordance with my invention;

Fig. 2 shows an enlarged detail view of a portion of the same; and

25 Fig. 3 shows a detail view taken on the line 3—3 of Fig. 1.

Referring to the accompanying drawings, the reference numerals 10 and 11 are used to indicate two mating sheets of metal, designated to be riveted or otherwise joined together. These metal sheets are placed in a compress and stamped with corrugations such as shown by the numerals 12, 13, 14 and 15. The numeral 15 indicates an endless 30 corrugation, preferably circular in conformation, stamped centrally in the sheet metal door, or other and simpler object, and the numerals 12, 13 and 14 indicate corrugations 35 radiating therefrom to the outer edge of the sheet metal door. The radiating corrugations join the central circular corrugation as shown, the apex of the radiating corrugation mating with or not extending beyond the apex of the circular corrugation, the inner 40 surface of the circular corrugation being perfectly smooth and undisturbed in its 45 contour by the joining of any other corrugation.

The steel door, or other object, may be 50 made of one piece of sheet metal stamped in this way, or it may be made up of a plurality of mating metal sheets which will be

joined by rivets or the like, to form in their entirety, the equivalent of a single sheet of metal. The corrugations may be stamped in the individual parts that go to make up one complete door before the parts are joined together, or they may be stamped subsequently to their joining without effecting my invention, the principal feature of which is to provide a circular corrugation centrally in the completed door, or other object, with radiating corrugations extending therefrom, as shown.

In practical construction it has been established that a door, or other object so constructed, will be able to withstand great stress, because each radiating corrugation ending in the circular corrugation which joins them all, will assist each and every corrugation in performing its function of providing strength. In such a construction there are no crossing intersections between the corrugations, such as has been found by the experiments and tests to make a weak point at the point of intersection. By my construction, all intersections are avoided and the circular central corrugation establishes and preserves the continuity of all the radiating corrugations.

It is also obvious that instead of a circular corrugation centrally of the plate, a corrugation of any conformation which is continuous and endless into which the radiating corrugations enter, in a manner similar to that shown in the drawings, may be used without in any way changing my invention, the object of which is to provide in a substantially central location in the plate, an endless and continuous corrugation from which lateral corrugations may radiate.

Having thus described my invention, what I claim and desire to secure by Letters Patent of the United States, is:

A sheet metal plate formed with an endless corrugation in its central portion with corrugations radiating therefrom to points adjacent the outer edges of said plate, the radiating corrugations being of substantially the same height as the central corrugation.

In testimony whereof I have signed the foregoing specification.

ROY A. NELSON.
